Attorney

UNITED STATES PATENT OFFICE

JACOB H. GRAVES, OF LEXINGTON, KENTUCKY

MILK-SHIPPING CABINET

Application filed October 30, 1928. Serial No. 316,020.

The object of the invention is to provide a refrigerator particularly adapted for the shipment of bottled goods, retaining them the while at a low temperature and permitting their ready removal in individual units, as when the device may be used in connection with a milk delivery carrier, or the like; to provide a refrigerating cabinet in the form of tiers of drawers of which certain of the same are adapted for the reception of the refrigerant, others for the catching of the evaporation therefrom and the remainder for the reception of the goods so that the latter may be arranged in orderly form; and to provide a device of this nature which is of simple construction and therefore susceptible of cheap manufacture and low marketing cost.

With this object in view the invention consists in a construction and combination of parts of which a preferred embodiment is illustrated in the accompanying drawings, wherein:

Figure 1 is a front elevational view of the invention.

Figure 2 and 3 are sectional views on the planes indicated by the lines 2-2 and 3-3 of Figure 1.

Figure 4 is a bottom plan view.

The invention consists of a cabinet 10 of which the top, bottom, side and back walls are heat insulated as indicated at 11 to prevent quick evaporation of the refrigerant. The cabinet is designed to support the drawers 12, 14 and 15, there being as many tiers of these drawers as desired and the number of drawers to a tier being dictated by the particular use to which the cabinet is put. In the illustrated embodiment there are two tiers of six drawers each. The drawer fronts are insulated as indicated at 16 and each drawer is provided with a pair of handles 17 to permit ready opening. The drawers do not penetrate the full depth of the cabinet, 45 but are of a depth materially shorter than the

depth of the cabinet to provide an air space 18 between them and the rear wall.

The drawers 12 are formed with reticulated bottoms 19 and are divided longitudinally and transversely with reticulated partition members 20 defining bottle receiving pockets 21.

The top drawers 14 have closed bottoms 22 which are transversely corrugated thus forming intercurrent ribs and gutters 22^a and 23. 55 These top drawers are designed for the reception of a refrigerant such as ice, and their bottoms are slightly inclined rearwardly so that the moisture from the refrigerant may be discharged at the rear ends of the gutters 60 into the air space 18, dropping into the drawers 15 of which the bottoms 24 are solid, the rear ends of the drawers 15 invading the air space 18. These drawers 15 constitute the means for catching the moisture from the 65 refrigerant which may be disposed of by withdrawing the drawers and pouring the contents into an appropriate waste.

By this construction, the contents of the several intermediate drawers 12 are subjected 70 to the cooling effect of the refrigerant and the contents of any one drawer is readily accessible by merely opening the drawer for the removal of such of its contents as is desired.

To provide for the ready shifting of the cabinet, it is equipped with casters 25 mounted on the bottom but hidden by the apron 26 surrounding the casters at the bottom.

Obviously the size of the cabinet, as well as the size of the drawers may be varied and the invention may be constructed in small units or in large units to suit any particular need without departing from the principle 85 involved.

The invention having been described what is claimed as new and useful is:

A refrigerator consisting of a cabinet and drawers arranged in tiers of which the top 90

and bottom drawers are respectively adapted for the reception of a refrigerant and the moisture therefrom and the intermediate drawers for the reception of goods to be cooled, the depth of all the drawers except the bottom drawer being less than the depth of the cabinet by an amount sufficient to provide a material air circulating space between them and the rear wall of the cabinet.

10 In testimony whereof he affixes his signature.

JACOB H. GRAVES.
